H. M. FISHERING.

SHADE TRIMMER.

APPLICATION FILED MAY 4, 1908.

898,732.

Patented Sept. 15, 1908.

UNITED STATES PATENT OFFICE.

HENRY MERCER FISHERING, OF CANTON, OHIO.

SHADE-TRIMMER.

No. 898,732.

Specification of Letters Patent.

Patented Sept. 15, 1908.

Application filed May 4, 1908. Serial No. 430,691.

To all whom it may concern:

Be it known that I, HENRY MERCER FISHERING, a citizen of the United States, residing at Canton, in the county of Stark and State of Ohio, have invented a new and useful Improvement in Shade-Trimmers, of which the following is a specification.

The invention relates to a machine for trimming the edge of a shade to a desired width and also for gaging the place for cutting off the end of the stick on which the shade is mounted. In devices of this class, it is customary to place the stick, with the shade fastened and rolled thereon, in suitable bearings, and to locate a cutting knife near but not touching the side of the shade roll; and to trim the shade by unrolling the shade and drawing it away from the stick and against the knife.

One object of the present improvement is to provide a knife which is automatically forced against the side of and into the shade roll, whereby the shade is positively cut without unrolling it from the stick, excepting that the trimmed strip may be unrolled after it is cut, and in so doing the shade roll is conveniently rotated for the cutting operation.

Another object of the improvement, is to provide means for adjusting the knife and for throwing and locking it out of contact with the shade roll when the trimming has been done; and to provide a base with adjustable slides therein for one of the shade bearings and for the cutting knife, together with clamps for both slides, and an extension scale or measure for the knife slide.

A further object of the improvement is to provide a yoke support for the protruding end of the shade stick, which may be adjusted against the trimmed edge of the shade, thus forming a suitable gage against which the superfluous portion of the stick can be cut off.

The invention, thus described in general terms, is illustrated in the accompanying drawings forming part hereof, in which—

Figure 1 is a plan view of the trimming machine showing a shade mounted on its stick in position for being trimmed by the cutting knife; Fig. 2, an enlarged cross section of the same on line 2—2, Fig. 1, showing also in broken lines the position of the knife when unlocked and impinging the side of the shade roll at the beginning of the cut-

ting operation; Fig. 3, a similar section showing the position of the knife at the completion of the cut; Fig. 4, an enlarged fragmentary plan view of the cutting knife at the completion of the cut; Fig. 5, an enlarged longitudinal section on line 5—5, Fig. 1, showing the yoke gage in position for cutting off the end of the stick.

Similar numerals refer to similar parts throughout the drawings.

The base-board 1 is provided with the two parallel longitudinal guide grooves 2 and 3, which are preferably dovetailed in cross section, and in which grooves the bearing slide 4 and the knife slide 5 are located and adapted to operate. The ordinary cam-clamps 6 are located in the recesses 7 in the sides of the base-board adjacent to the respective slides, by means of which clamps the slides are adapted to be locked in any desired position.

The fixed bearing 8 is provided on one end of the base-board, directly over the line of the bearing slide, and the adjustable bearing 9 is provided on the opposite end of the same slide; the fixed bearing being adapted to receive the pivot 10 located in the spring end of the shade stick 11, and the adjustable bearing being adapted to receive the fixed pivot 12 on the other end of the shade stick—the end on which the shade is usually trimmed and from which the surplus length of the stick is cut. It is evident that the shade stick, with the shade 13 rolled thereon, can be readily placed in the machine by first inserting the spring pivot of the stick in the fixed bearing and then by suitably sliding the adjustable bearing to receive the fixed pivot on the other end of the stick; in which position the adjustable bearing is locked by operating one or more of the clamps against the side of its slide. The elastic bands or rings 14 are preferably clamped around the shade roll, one near each end, for the purpose of keeping the same tightly rolled while the shade is being trimmed and the stick cut off; the ring near the end of the shade to be trimmed being located inside the proposed trimmed end of the roll.

The knife bracket 15 is formed or attached on the knife slide and the knife arm 16 is rotatably mounted thereon, preferably by means of the pivot pin 17 located parallel with the axis of the shade stick. The cutting knife 18 is fastened in the slot 19 in the head 20 of the knife arm, in which slot the

knife is adapted to be adjusted and fastened by means of the thumb screw 21. The cutting end 22 of the knife, is preferably pointed, and is sharpened by beveling one side only, 5 thus presenting a flat side to squarely abut the trimmed end of the shade roll, as shown in Fig. 4; and the parts are so located and arranged that the pointed end of the knife is presented to the side of the shade roll. In 10 the cutting operation, the knife arm is automatically rotated to forcefully impinge and impress the knife point against and into the side of the shade roll by means of the comparatively strong spring 23, which is preferably in the form of a spiral spring located around the hub 24 of the knife arm; and for 15 normally holding the knife away from the roll, the spring latch 25 is provided on the knife bracket and is adapted to engage the pin 26 on the side of the knife arm, when the knife is rotated away from the curtain roll, as shown in Fig. 2.

The primary measuring scale 27 is provided on the face of the base-board along the 20 outer side of the knife slide, and this scale begins at zero, located at a point opposite the edge of the shade on the spring end of the stick, and extends thence preferably a distance of 24 inches, the same being designated 25 in inches from 1 to 24. The extension scale 30 28 is provided on the face of the knife slide, and begins at the knife and thence extends in a reverse direction along the primary scale, a distance of 24 inches, the same being designated 35 in inches from 24 to 48. It is evident 40 that when the knife slide is moved one way, its distance in inches from the edge of the curtain on the spring end of the stick, is indicated by the primary scale, and that when the knife slide is moved the other way, the 45 distance of the knife from the same edge of the curtain is indicated by the number on the extension scale which registers with the arrow located at 24 inches in the primary scale, this distance being 34 inches as illustrated in Fig. 1.

In fitting a shade for a desired width of window, the next width of shade material in excess of the desired width is selected from 50 stock, and the same is fastened and rolled on a stick which is likewise of the next stock length in excess of the proper length, one edge of the shade being located at a suitable marginal distance from the spring end of the shade. Two or more elastic bands are then 55 preferably telescoped around the shade to hold the same tightly on the stick, and the stick, with the shade rolled thereon, is then placed in the bearings of the cutting machine. The spring latch is then released 60 from engagement with the knife arm, which is rotated by its spring, and the point of the knife impinges the side of the shade roll. The shade roll is then rotated by hand until 65 the folded-end edge of the shade is cut by the

knife; whereupon, the end of the cut strip is grasped by the hand, and pulled away from the roll, as shown by broken lines in Fig. 2, and in the rotation of the shade roll caused thereby, the pressure of the point of the 70 knife forces the same into the roll, whereby the strip is continuously cut until the knife goes entirely through the roll and into the stick, as shown in Fig. 3; after which the knife arm is rotated away from the stick, and is held in its normal position by means of the spring latch.

The stop shoulder 29 is preferably provided on the knife arm and the adjustable stop screw 30, on the knife bracket, which 80 serve to limit the movement of the knife arm towards the shade stick; but it is evident that as the point of the knife is adapted to be stopped against the shade stick, as shown in Fig. 3, the stop shoulder and screw are not 85 essential features of the device. Furthermore, the spring latch is not an essential feature for the proper operation of the knife in cutting the shade, but it is a very convenient adjunct for normally holding the knife 90 arm against the action of its spring while one shade is being removed and another inserted in the machine. It is also evident that it is not essential to point the cutting end of the 95 knife, but it is more effective to do so; and furthermore, that the cutting knife can be manipulated by the hand of the operator, in which event the spring can be dispensed with, but it is preferred to use the spring so that the action of the knife will be automatic. 100

The adjustable bearing 9 is preferably hinged to the bearing slide, and formed on or hinged thereto is the yoke 31 which is located in a horizontal position when the adjustable bearing stands in a vertical position; and it is evident that by disengaging the bearing from the pivot on the end of the stick, the yoke can be rotated to the vertical position, as shown in Fig. 5, in which position it is adapted to be held by means of the 105 spring 32 acting against the end of the bearing. The protruding end of the stick is then placed and supported between the embracing arms of the yoke, which is adjusted by moving the bearing slide to bring the yoke against 110 the trimmed end of the shade roll intermediate the ends of the stick, in which position the yoke forms a suitable gage on the outer side of which the stick is cut at a suitable distance from the trimmed end of the roll; and, after the stick is removed, the yoke is rotated 115 to its horizontal position which brings the adjustable bearing to its vertical position ready for receiving the pivot pin of another shade stick.

It is evident that it is neither essential to hinge the yoke or the adjustable bearing on the slide, nor to make the yoke integral with the bearing, as illustrated and described herein, but it is very convenient to form and 125 130

attach the parts in this manner for the purpose of readily substituting the one for the other as a support for the shade stick during the performance of their respective functions.

5 Neither is it necessary that the yoke should support the shade stick, unless the adjustable bearing is disengaged from the fixed pivot of the shade stick before the yoke is placed in position, as is done in the embodiment of the 10 invention disclosed herein.

The machine is designed to be used on a table, and the feet 33, preferably of rubber, are provided on the bottom of the base-board, to prevent a defacement of the table.

15 The similar feet, as 33^a, are also provided on the ends of the slides, which latter feet are formed with the shanks 34, which shanks are adapted to enter into the slots 35 formed in the corresponding end of the base-board.

20 These slots are only extended a short distance into the base-board, and when it is necessary to move the slides inward beyond the limits of the slots, the feet 33^a are detached from the ends of the slides.

25 What I claim as my invention, and desire to secure by Letters Patent, is—

1. A mounted-shade trimming-machine including a base with pivot-bearings thereon for the shade-stick, a knife on the base having one end pointed and sharpened and presented to the side of the shade-roll, with means for moving the knife to impinge and impress its point against and into the side of the shade-roll, and means for releasably holding the knife away from the roll.

2. A mounted-shade trimming-machine including a base with pivot-bearings thereon for the shade-stick, a knife on the base having one end pointed and sharpened and presented to the side of the shade-roll, with means for moving the knife to impinge and impress its point against and into the side of the shade-roll.

3. A mounted-shade trimming-machine including a base with pivot-bearings thereon for the shade-stick, a knife on the base having one end pointed and sharpened and presented to the side of the shade-roll and adapted to cut into the same.

50 4. A mounted-shade trimming-machine including a base with pivot-bearings thereon for the shade-stick and a knife on the base presented to the side of the shade-roll and adapted to cut into the same, the knife being

flat on one side to squarely abut the trimmed 55 end of the shade-roll.

5. A mounted-shade trimming-machine including a base with pivot-bearings thereon for the shade-stick, a knife on the base presented to the side of the shade-roll with automatic means for moving the knife to cut into the side of the roll.

6. A mounted-shade trimming-machine including a base with pivot-bearings thereon for the shade-stick and a knife on the base 65 presented to the side of the shade-roll and adapted to forcefully cut into the same.

7. A mounted-shade trimming-machine including a base with pivot-bearings thereon for the shade-stick, a slide in the base parallel with the shade-stick, a primary scale on 70 the base and an extension scale on the slide, and a knife on the slide adapted to cut the shade.

8. A mounted-shade trimming-machine 75 including a base with pivot-bearings thereon for the shade stick, a knife-slide in the base parallel with the shade stick, a primary scale on the base and an extension scale on the slide.

80 9. In a mounted-shade trimming-machine, a base with a slide therein, a bearing on the base over one end of the slide and a bearing hinged to the other end of the slide adapted to support the shade-stick, the hinged bearing having a yoke thereon adapted to be moved to support the stick and to be adjusted by a movement of the slide against the trimmed end of the shade-roll.

10. In a mounted-shade trimming-machine, a base having a bearing on one end and a hinged adjustable bearing on the other end adapted to support the shade stick, the hinged bearing having a yoke thereon adapted to be rotated to support the stick and to be adjusted against the trimmed end of the shade-stick.

90 11. In a mounted-shade trimming-machine, a base having bearings thereon adapted to support the shade-stick and a gage on 100 the base adapted to be adjusted to embrace the stick intermediate its ends and to abut the trimmed end of the shade-roll.
